**GARMENT FOR HOLDING WORKMEN
AGAINST FALLING**Roland Robert Hlacia, 36 Rue Chauveau,
Neuilly-sur-Seine, France

Filed July 5, 1962, Ser. No. 207,737

Claims priority, application France, July 7, 1961,
867,224, Patent 1,301,410
4 Claims. (Cl. 182—3)

Various legal and governmental regulations require, in all countries, contractors and manufacturers to supply their workmen assigned to jobs during which they risk falling, with protecting means and apparatus adapted to prevent serious and even less serious accidents.

Unfortunately, the protecting means proposed hitherto are heavy and bulky and are liable sometimes to injure the workmen, in particular on the spine or by breaking the workmen's ribs, and for this reason, even when such apparatus are actually available to the workmen, the latter are reluctant to use them and even refuse their use.

My invention relates to dungarees, boiler suits or the like garments incorporating a safety working harness comprising a strap of yielding and light material, which is also resistant as in the case of nylon or of any other animal or vegetable fibres.

Said straps or harnesses form, on the one hand, two loops passing around the workman's thighs and extending in proximity with the crotch and, on the other hand, two other loops connected each with one of the preceding loops and passing over the workman's shoulders, while two attaching points at least are provided over the chest of the workman, at which points the harness may be secured to a stationary point by means of a rope.

The harness or strap may be associated with a belt rigid with said harness or otherwise. The harness or strap may also be incorporated with the boiler suit or the like garment and it may be sewn entirely or partly inside the garment, or else, it may engage loops or keepers on the garment. It may also be fitted entirely or partly inside sheaths rigid with said garment.

The whole arrangement may be associated with a belt rigid with the strap or otherwise and/or further straps surrounding the thighs and secured to the garment, either partly or completely.

The strap is positioned preferably inside the garment so as to form two double loops which do not increase substantially its weight while the garment retains its essential yieldingness and allows thus the workman or the like user to execute, without being hindered, all the movements required for accomplishing the job assigned to him. At certain predetermined points, the strap or harness extends outside the dungarees, so as to form as many loops for the engagement and securing of a safety member such as split rings, snap rings, connected with safety ropes and the like.

The whole arrangement may be finished by a belt-forming strap and a further auxiliary half belt engaging the hips and it is also possible to associate with this arrangement a further loop-forming strap fitted around each thigh, so as to cooperate in holding the garment fast on the body in case of a fall.

The accompanying drawings illustrated, by way of example, a preferred embodiment of my improved safety garment. In said drawings—

FIG. 1 is a front view of a man wearing such a garment.

FIG. 2 shows him as seen from the back.

FIG. 3 shows the actual harness independently of the garment, as sewn inside the dungarees which are not illustrated for sake of clarity, together with the manner of forming the original strap into two double loops.

2

FIG. 4 is a view similar to FIG. 3 showing a modification in the loops of the harness.

As illustrated, my improved safety garment comprises generally a so-called boiler suit or dungarees which may be made of any desired fabric.

Inside the garment is sewn a safety harness 2 formed by a continuous strap sewn together or otherwise and made of any synthetic, animal or vegetable material. Said strap forms loops as illustrated in particular in FIG. 3 and also in FIG. 4 illustrating a modification. The loops G and H are to be fitted over the wearer's shoulders and the loops I and J under his thighs.

Said strap should have a resistance against breaking of at least 1,000 to 1,400 kg. The harness may be associated with a belt 3 made out of a strap of the same type,

10 while a further strap 4 extending preferably in parallel with the belt strap 3 is adapted to engage the hips. It is also possible to resort to two further straps 5 surrounding the thighs above the knees.

15 20 The different sections of the harness strap project outwardly beyond the inside of the garment so as to form at the points shown by hatchings A, B, C, D, E, small loops, or keepers through which the strap engages the garment, said keepers serving chiefly for the engagement of safety members at D and E in registry with the pectorals, B and C at the hips and A in the back of the wearer.

25 Similarly, each of the thigh straps 5 may be provided with an outer keeper F.

30 The points of crossing of the strap sections at A, B, C are carefully constructed, so as to ensure a constant relative position between said sections as provided for instance by providing therefor keepers or sheaths to hold them on the garment.

35 As soon as my improved safety garment has been put on, it protects entirely the wearer, since three types of attachments are available, to wit:

A bracing attachment obtained by securing the safety rope to the interconnected sections A in the back of the wearer,

40 An anchoring attachment obtained by securing the anchoring rope to the crossing points registering with the hips at B and C;

45 A safety attachment preventing falls over considerable heights as provided by inserting a safety rope underneath the pectoral loop section D, E.

It should be mentioned that the working implements may also be easily secured to the crossing of the sections on the hips at B and C.

The garment disclosed cannot disturb in any manner 50 the movements of the wearer and it is not necessary to fasten the belt 3 or to close the garment for working, although it cooperates in the safety obtained.

55 The pressures to which the wearer may be subjected when falling are reduced by the presence of the fabric forming the garment which is, in principle, secured to the actual harness, whatever may be the manner of securing such a harness to the garment.

Experience has shown that the strap or harness may be used on an almost completely bare body, but it is then 60 preferable to resort to a sheathed strap which, in case of a fall, allows a slight shifting of the strap, while the sheath remains adherent to the wearer's body. This reduces the possible ecchymoses on the body of the wearer when falling fortuitously.

65 Lastly, instead of resorting to a boiler suit, the garment may be reduced to mere overalls with long or short legs, or even to breeches.

70 The applications of my improved garment are manifold and only a few of them may be mentioned hereinafter by way of a mere exemplification and in a non-exhaustive manner: public works, buildings, various plants, timbering, quarries, wells, laying of pipes, digging of pits, con-

struction of vats, roofs, window-framing, general upkeep, bridge building.

It may also serve for orcharding and wood cutting and also in certain sports such as Alpinism, speleology and the like.

What I claim is:

1. A safety harness comprising a strap passing successively from a crossing point on the wearer's back between his shoulders up over his right shoulder, downwardly over the right side of his chest, rearwardly about his right buttocks, downwardly and forwardly through his crotch, upwardly and rearwardly crossing, on the wearer's right side above the hip, the portion extending downwardly on the right chest, then continuing upwardly and rearwardly about the wearer's body to said crossing point, said strap continuing from the crossing point up over the wearer's left shoulder, downwardly over the left portion of his chest, rearwardly about his left buttocks, downwardly and forwardly through the wearer's crotch, then upwardly and rearwardly crossing, on the wearer's left side above the hip, the portion extending downwardly on the left chest, then continuing upwardly and rearwardly about the wearer's body to said crossing point at the wearer's back, forming loops embracing the shoulders and thighs of the wearer.

2. A safety harness according to claim 1 encased in a body-embracing garment and having portions extending through to the exterior of the garment at the crossing points of the strap at the wearer's back, above the wearer's hips and each side of the wearer's chest to provide regions for attachment to one end of a flexible safety member.

3. A safety harness comprising a first strap passing successively from a crossing point on the wearer's back

between his shoulders up over his right shoulder, downwardly over the right side of his chest, rearwardly about his right buttocks, downwardly and forwardly through his crotch, upwardly about the wearer's left thigh, rearwardly above the wearer's left hip to said crossing point, and a second strap passing successively from said crossing point up over the wearer's left shoulder, downwardly over the left side of his chest, rearwardly about his left buttocks, downwardly and forwardly through his crotch, about the wearer's right thigh, rearwardly above the wearer's right hip to said crossing point, said straps crossing at said crossing point at the wearer's back and above each hip, and forming loops embracing the wearer's shoulders and thighs.

4. A safety harness according to claim 3 encased in a body-embracing garment and having portions extending through to the exterior of the garment at the crossing points of the strap at the wearer's back, above the wearer's hips and each side of the wearer's chest to provide regions for attachment to one end of a flexible safety member.
